JUICING MACHINE

Frederick L. McCulloch, Tampa, Fla.

Application December 22, 1948, Serial No. 66,769

14 Claims. (Cl. 100—35)

1

This invention is a novel juicing machine and the principal object thereof is to provide a machine particularly adapted for the commercial juicing of fruits, such as citrus fruits, for canning purposes, in a continuous or substantially continuous process.

Further objects of the invention are to provide a machine of the above type having certain novel features of construction hereinafter set forth.

I will explain the invention with reference to the accompanying drawings, which illustrate one practical embodiment thereof to enable others familiar with the art to adopt and use the same; and will summarize in the claims, the novel features of construction, and novel combinations of parts, for which protection is desired.

In said drawings:

Figure 1 is an elevation of one side of my novel machine;

Fig. 2 is an opposite side elevation of one end thereof, showing the rind ejecting means and the cup deflecting cam means;

Fig. 3 is an enlarged longitudinal section through said machine;

Fig. 4 is a vertical transverse section on the broken line 4—4, Fig. 3.

Fig. 5 is an enlarged top plan view of one of the cups, also showing the cup supporting chain links;

Fig. 6 is a side elevation of the parts shown in Fig. 5; and

Fig. 7 is a transverse section on the line 7—7, Fig. 5.

As shown, my novel juicing machine comprises a base 1 having spaced pairs of uprights 2 and 3 thereon connected at their upper ends at each side by spaced horizontal members 4, to form a rigid structure. Intermediate the ends of the members 4 are a spaced pair of uprights 5.

At the upper ends of uprights 5 is a shaft 6 upon which is journaled a disc 7 carrying a plurality of spokes 8 extending radially and spaced evenly apart, twelve such spokes 8 being shown in Fig. 1. At the outer end of each of the spokes 8 are mounted pressers 9 which are in the form of cups having tubular hubs 9a, Fig. 4, which are slidably mounted on the outer ends of the spokes 8, the hubs having slots 9b, Fig. 4, therein receiving pins 10 transfixing the spokes 8 and passing through the slots 9b so as to permit the pressers 9 to have a limited axial movement on said spokes. Interposed around the hubs 9a between the pins 10 and the bases of the pressers 9 are springs 11 normally urging the pressers 9 outwardly of the spokes 8 to their maximum extent limited by the pins 10 in the slots 9b. The wheel 7 is not positively driven, but is freely rotatable upon the shaft 6.

Upon the frame members 4 mounted in bearings 12, Figs. 1 and 3, is a shaft 14 carrying a pair

2

of spaced parallel drive wheels 13 having a series of opposed notches 13a in their peripheries. As shown in Fig. 1, the spaced wheels 13 are provided with eleven notches 13a in their peripheries. Wheels 13 are keyed upon shaft 14 and one end of shaft 14 carries a drive pulley 15 (Fig. 1) or the like, around which runs a belt 16 for rotating the pair of wheels 13 in unison.

At the opposite end of frame members 4 are bearings 17 for a shaft 18 upon which are mounted spaced wheels 19 having notches 19a in their peripheries which are similar to the notches 13a of wheels 13, said wheels 19 being of a somewhat smaller diameter than wheels 13, and as shown same have seven notches 19a in their peripheries.

The pairs of wheels 13 are driven in the direction of the arrows A and B, Fig. 3, by a belt 16 (Fig. 1) or the like, the wheels 19 being rotated therewith by an endless series of cups 20 shown in detail in Figs. 5, 6 and 7. Each cup 20 is preferably square in plan and is provided with a closed bottom 20a having a longitudinal slot 20b, Fig. 5, and a transverse or cross slot 20c therein for the purpose hereinafter described. Within each cup-shaped member 20 is a circular lining 21 of external diameter substantially equal to the internal dimensions of the cup 20 as shown in Fig. 5, lining 21 being adapted to directly receive and center within the related cup 20 the fruit or the like which is delivered thereto by a chute 22, Figs. 1 and 3, as the cup approaches the upper run of the endless series of cups, the fruit in chute 22 moving in the direction of the arrow C, and one fruit, such as an orange, being delivered by chute 22 into each cup 20 as it passes the lower end of the chute. The fruit thus delivered is centered within the lining 21 of cup 20 by means of inverted U-shaped flat or round springs 23, Figs. 5, 6 and 7, at the corners of the cup, each spring 23 having one leg anchored in the bottom 20a of the cup adjacent a corner thereof, the spring extending upwardly and inwardly over the lining 21 with its outer portion yieldably extending radially downwardly within the lining 21. The springs 23 also will hold any small size fruit up above the bottom of the cup 20 so that the presser 9 will strike the tops thereof before the fruit is engaged by the cross-knives 31b, 31c, hereinafter described. If the springs 23 were not used, the knives would also otherwise push the fruit out of centered position in the cup 20.

As shown, each cup 20 is provided adjacent its rear end with oppositely extending non-rotatable lugs 24, and pairs of links 25 connect the lugs 24 of adjacent cups 20, said links 25 having bearings 25a at each end directly receiving the lugs 24 to form a pair of spaced endless chains connecting the series of cups 20 together for per-

mitting the endless series of cups 20 to pass around the wheels 13 and 19. The lugs 24 are of such length that in passing around the wheels 13 and 19 the lugs automatically engage the notches 13a and 19a, the wheels 13 and 19 rotating at the same peripheral speed. The lugs 24 at one side of the cups are provided with rollers 26, as shown in Figs. 5, 6 and 7, rotatably mounted thereon beyond the links 25 and secured by washers 26a and nuts 26b for the purpose hereinafter set forth.

The spacing of the cups 20 and the pressers 9 is such that as the endless series of cups 20 pass around the wheels 13 and 19, Fig. 3, the successive pressers 9 will be entered into the successive linings 21 of the cups and will yieldably engage the fruit in the bottoms 20a of the cups, the wheel 7 being driven solely by engagement of the pressers 9 in the moving series of cups 20.

Means are provided for splitting or cutting the bottoms of the fruit carried by the upper run of the series of cups 20 simultaneously with the entry of the plungers 9 into the cups, i. e. as the cups approach the presser wheel 7. As shown, the uprights 5, Figs. 1 and 3, are provided with lateral extensions 27, Figs. 1, 3 and 4, in which are journalled a shaft 28 having collars 29 at each, which collars 29 are pinned or otherwise secured to shaft 28, the collars contacting the outer faces of the extensions 27. Adjacent one lateral extension 27, and at the same side as the rollers 26, is a star wheel 30 having arms 30a, five arms being shown in Fig. 1, the outer ends of which are rounded as at 30b, Fig. 1, and are adapted to directly engage the rollers 26 carried by the cups 20, said rollers 26 reducing friction. Successive arms 30a successively engage successive rollers 26 so as to cause shaft 28 to rotate in unison with the movement of the endless series of cups 20 in the upper run. Star wheel 30 is keyed to the shaft 28 which also carries in vertical alignment with the endless series of cups 20 a star shaped cutting wheel 31, Fig. 3, having arms 31a corresponding with the arms of the star wheel 30, the outer ends of the arms 30a being provided with semi-circular cross-knives 31b and 31c respectively disposed at right angles to each other and adapted, as the series of cups is moved in the direction of the arrows A and B, Fig. 3, to successively enter upwardly through the cross slots 20b, 20c in the bottoms of the cups 20, and cut a cross-shaped incision in the bottom of the fruit in the related cups 20 as the related pressers 9 come into contact with the tops of the fruits, so that as the cups move in the direction of the arrows A, B, Fig. 3, the juice will be extracted from the fruit when the cup 20 is moved to the position wherein the related spoke 8 is disposed in vertical downward position, the related presser 9 subsequently receding from the cup and the extracted juice being discharged through the slots 20c, 20b in the bottom of the cup. The number of arms 31a on the cutting wheel 31 is such that the cross-knives 31b, 31c, will enter each of the cups 20 as the same pass across the upper run of an endless series of cups 20.

Each cup 20 is hinged on the chain links 25 at one end by the lugs 24, while the opposite end of the cup is prevented from being deflected downwardly out of the plane of the chains 25 under action of the pressers 9 by means of inwardly projecting lugs 25x, Figs. 1, 5, 6 and 7, on the chain links 25 adapted to underlie the leading end of the cup 20 to maintain the cups when traversing the upper run of the endless series

in substantially the plane of the chain links 25, thus providing a firm support for the cups during the juicing operation. As shown in Figs. 1 and 3 each lug 25x is also extended sufficiently forwardly of the leading end of the cup 20 to underlie the trailing end of the preceding cup, to prevent the cup 20 from swinging or hinging downwardly while traversing the lower run of the chain links 25 while passing the spray jets and while moving around towards the feed chute 22.

In order that the chain links may be readily assembled around the wheels 13 and 19, one of the pairs of links 25 as shown in Figs. 1, 3, 5 and 6 are formed into overlapping sections 25m and 25n, the overlapped portions of the sections being thin and being secured together by means of removable screws 32 (Fig. 5) so that the pair of chains may be readily separated or connected by removal of or replacement of the screws 32.

The juice which is extracted from the cups 20 by the pressers 9 drops through the slots 20b, 20c of cups 20 into a tank 33 which has parallel sides so spaced as to substantially embrace the width of the cups 20 and to house the cutting wheel 31, as shown in Fig. 4, the ends of the tank 33 contracting at their lower end and communicating with a lateral outlet duct 34, Figs. 1 and 4, leading out of the machine in order that the extracted juices may be readily collected in a suitable container. A clean-out hole 35 is provided in the lower end of the tank 33 substantially opposite the outlet pipe 34, said hole being normally covered by a closure plate 36 whereby any pulp or other solid matter which may collect in the bottom of the tank 33 and which would tend to clog the outlet 34, may be readily removed.

On the frame uprights 3 are lateral extensions 37 in which is journalled a shaft 38 on which is mounted an ejector star wheel 39 having blades 39a adapted when the cups 20 are successively brought opposite the said cups 20 to enter therein and to extract the rind of the fruit, the wheel 39 being rotated merely by the movement of the cups 20, and the spacing of the blades 39a being such as to enter successively into the slots 20b of the cups as same are successively brought opposite the said wheel 39.

The ejected rinds drop onto an endless conveyor belt 40 which is mounted under the wheel 39 and is driven in any desired manner in the direction of the arrow D, Fig. 3, said belt 40 having its inner end running around a pulley 41 mounted on a shaft 42 journalled in the uprights 3 as shown, the rinds being thereby conveyed to a point of disposal.

In order to insure that the cups while nearing the ejector wheel 39 will be properly seated on the lugs 25x of the chain links 25, a cam 50, Fig. 2, is provided at the discharge end of the machine, said cam 50 having an arcuate surface 50a which is substantially parallel with the periphery of the wheels 13 but is disposed inwardly thereof, said cam surface 50a being contacted by pins 51 which are respectively mounted on the lugs 24 of the cups 20 at the side opposite from the rolls 26. By the use of the cam 50 and the pins 51, in event any of the cups, before reaching the ejector wheel, may have been pivoted away from contact with the lugs 25x of the chains, the engagement of the pins 51 with the cam surface 50a will immediately restore the cups to their normal position shown in Fig. 2 so that the same will be properly positioned with respect to the chain links 25 when reaching the ejector wheel 39.

At the feeding end of the machine is a cam

plate 71 (Fig. 3) mounted on brackets 72 and 73 secured to the adjacent end of tank 33 between the wheels 19, said plate 71 having an outer curved cam surface 71a disposed closely adjacent the under sides of the cups 20, so that in event any of the cups 20 should be hinged or swung, just prior to passing under the feed chute 22 while rounding the wheels 19, out of proper parallel relation with respect to their related chain links 25 the trailing ends of the hinged cups 20 will contact the cam surface 71a and thereby be properly positioned as shown in Fig. 3 parallel with the chain links 25 to receive the fruit discharged from the chute 22 prior to passing under the presser wheel 7.

Beneath the lower run of the cups 20 is a pan 55 for receiving the liquid and the rinsed matter from the cups 20, the rinsing being effected at the lower run of the series of cups by means of a spray head 56 disposed below the lower run of the endless series, and an offset spray head 57 disposed above the lower run of the endless series as shown in Fig. 1, said spray being supplied with clean water or the like, under pressure, so as to thoroughly wash the cups 20 as they proceed to and under the feed chute 22, Fig. 1. The pan 55 may be drained in any suitable manner. Above the spray head 56 is a baffle 70 (Fig. 1) to prevent the water from the head which is directed upwardly through the cups 20 from passing into the interior of the machine, thus maintaining the said interior relatively dry during operation of the machine.

Between the spray head 57 and the chute 22 is a hot air or vapor jet 58, Fig. 1, mounted upon a bracket 59 which may be conveniently secured to the uprights 2, said jet 58 being supplied with hot air or vapor from any suitable source, the jet being directed into the interior of the cups 20 just prior to their passage under the feed trough 22 for the purpose of blowing out any surplus water therein which may have been deposited by the spray heads 56 and 57, and the heated vapors further serving to some degree to partially dry the interior of the cups before receiving fruit from the chute 22.

I do not limit my invention to the exact form shown in the drawings, for obvious changes may be made therein within the scope of the claims.

I claim:

1. A machine for extracting juices from fruit or the like, comprising spaced pairs of wheels having opposed spaced notches in their peripheries, one pair of wheels being driven; an endless series of cups having a substantially horizontal upper run running around said spaced pairs of wheels, said cups having oppositely extending lugs adjacent their rear ends adapted to successively engage the successive notches of said wheels; pairs of chain links connecting adjacent pairs of lugs; a presser wheel above the upper run of said series of cups; a radially disposed series of yieldably mounted pressers carried by said wheel and adapted to successively engage successive cups of the series as the upper run moves thereunder, each cup being of square shape and having a cross-shaped slot; a circular lining within each cup having an opening coaxial with said slot; and inverted U-shaped springs, each having one leg anchored adjacent a corner of the cup, said springs extending radially over the lining and having their free ends extending downwardly towards the center of the lining.

2. A machine for extracting juices from fruit or the like, comprising a base; spaced pairs of

wheels journalled on said base having opposed spaced notches in their peripheries, one pair of wheels being driven; an endless series of cups having a substantially horizontal upper run running around said pairs of wheels, said cups having oppositely extending lugs adjacent their rear ends adapted to successively engage the successive notches of said wheels; pairs of chain links connecting adjacent pairs of lugs; a presser wheel 10 journalled on the base above the upper run of said series; a radially disposed series of yieldably mounted pressers carried by said wheel and adapted to successively engage successive cups of the series as the upper run moves thereunder; 15 said cups having slots in their bottoms; means for feeding fruit into the successive cups as they approach said upper run; means adapted to enter the slots in the successive cups to slit the fruit therein as the pressers engage the tops of the 20 fruit; and means for collecting the juice which drops through the slots of the cups in the upper run.

3. In a machine as set forth in claim 2, said fruit slitting means comprising a knife wheel 25 journalled on the base having arms adapted to successively enter the slots in the cups of the upper run; knives on said arms adapted to enter the slots; and a star wheel rotatable with said knife wheel having arms adapted to successively 30 engage the lugs of the successive cups to rotate the knife wheel synchronously with the movement to the cups.

4. In a machine as set forth in claim 2, said juice collecting means comprising a tank having 35 its upper end underlying the series of cups in the upper run below the presser wheel and housing the slitting means, the lower end of the tank contracting into an outlet discharging laterally of the machine; said tank having an access opening 40 opposite the outlet; and a removable cover plate closing said opening.

5. In a machine as set forth in claim 2, inwardly extending projections on the pairs of links underlying the leading ends of each cup and the 45 trailing end of the preceding cup and adapted to maintain the cups of the upper run disposed in the plane of the links while passing under the presser wheel.

6. In a machine as set forth in claim 5, means 50 for ejecting the rinds from the cups as the cups approach the lower run; and cam means on the base cooperating with pins on the lugs for seating the cups on the projections just prior to the cups reaching the ejecting means.

7. In a machine as set forth in claim 5, cam 55 means on the base adapted to contact the under sides of the cups for seating the cups on the projections just prior to the cups reaching the feeding means.

8. In a machine as set forth in claim 2, each cup being of square shape, said slots in each cup being cross-shaped; a circular lining within each cup having openings coaxial with said slots; and inverted U-shaped springs, each having one leg 60 anchored adjacent a corner of the cup, said springs extending radially over the lining and having their free ends extending downwardly towards the center of the lining.

9. In a machine as set forth in claim 2, said 70 presser wheel having a series of radially disposed spokes thereon; said pressers having hubs slidably mounted on said spokes; pins transfixing said spokes and passing through elongated slots in said hubs; and springs interposed between the pins and the bottoms of said pressers.

10. A machine for extracting juices from fruit or the like, comprising a base; spaced pairs of wheels journalled on said base having opposed spaced notches in their peripheries, one pair of wheels being driven, an endless series of cups having a substantially horizontal upper run running around said pairs of wheels, said cups having oppositely extending lugs adjacent their rear ends adapted to successively engage the successive notches of said wheels; pairs of chain links connecting adjacent pairs of lugs; a presser wheel journalled on the base above the upper run of said series; a radially disposed series of yieldably mounted pressers carried by said wheel and adapted to successively engage successive cups of the series as the upper run moves thereunder; said cups having slots in their bottoms; means for feeding fruit into the successive cups as they approach said upper run; means adapted to enter the slots in the successive cups to slit the fruit therein as the pressers engage the tops of the fruit; means for collecting the juice which drops through the slots of the cups in the upper run; means for ejecting the rinds from the cups as the cups approach the lower run, said fruit slitting means comprising a knife wheel journalled on the base having arms adapted to successively enter the slots in the cups of the upper run; arcuate knives on said arms adapted to enter the slots in the successive cups; and a star wheel rotatable with said knife wheel having arms adapted to successively engage the lugs of the successive cups to rotate the knife wheel synchronously with the movement to the cups.

11. A machine for extracting juices from fruit or the like, comprising a base; spaced pairs of wheels journalled on said base having opposed spaced notches in their peripheries, one pair of wheels being driven, an endless series of cups having a substantially horizontal upper run running around said pairs of wheels, said cups having oppositely extending lugs adjacent their rear ends adapted to successively engage the successive notches of said wheels; pairs of chain links connecting adjacent pairs of lugs; a presser wheel journalled on the base above the upper run of said series; a radially disposed series of yieldably mounted pressers carried by said wheel and adapted to successively engage successive cups of the series as the upper run moves thereunder; said cups having slots in their bottoms; means for feeding fruit into the successive cups as they approach said upper run; means adapted to enter the slots in the successive cups to slit the fruit therein as the pressers engage the tops of the fruit; means for collecting the juice which drops through the slots of the cups in the upper run; means for ejecting the rinds from the cups as the cups approach the lower run, said juice collecting means comprising a tank having its upper end underlying the series of cups in the upper run below the presser wheel and housing the slitting means, the lower end of the tank contracting into an outlet discharging laterally of the machine; said tank having an access opening opposite the outlet; and a removable cover plate closing said opening.

12. A machine for extracting juices from fruit or the like, comprising a base; spaced pairs of wheels journalled on said base having opposed spaced notches in their peripheries, one pair of wheels being driven, an endless series of cups having a substantially horizontal upper run running around said pairs of wheels, said cups having oppositely extending lugs adjacent their rear ends

adapted to successively engage the successive notches of said wheels; pairs of chain links connecting adjacent pairs of lugs; a presser wheel journalled on the base above the upper run of said series; a radially disposed series of yieldably mounted pressers carried by said wheel and adapted to successively engage successive cups of the series as the upper run moves thereunder; said cups having slots in their bottoms; means for feeding fruit into the successive cups as they approach said upper run; means adapted to enter the slots in the successive cups to slit the fruit therein as the pressers engage the tops of the fruit; means for collecting the juice which drops through the slots of the cups in the upper run; means for ejecting the rinds from the cups as the cups approach the lower run, said ejecting means comprising a star wheel journalled on the base having arms adapted to successively enter the slots of successive cups and to lift the rinds out of the cups; and an endless conveyor belt receiving the discharged rinds.

13. A machine for extracting juices from fruit or the like, comprising a base; spaced pairs of wheels journalled on said base having opposed spaced notches in their peripheries, one pair of wheels being driven, an endless series of cups having a substantially horizontal upper run running around said pairs of wheels, said cups having oppositely extending lugs adjacent their rear ends adapted to successively engage the successive notches of said wheels; pairs of chain links connecting adjacent pairs of lugs; a presser wheel journalled on the base above the upper run of said series; a radially disposed series of yieldably mounted pressers carried by said wheel and adapted to successively engage successive cups of the series as the upper run moves thereunder; said cups having slots in their bottoms; means for feeding fruit into the successive cups as they approach said upper run; means adapted to enter the slots in the successive cups to slit the fruit therein as the pressers engage the tops of the fruit; means for collecting the juice which drops through the slots of the cups in the upper run; means for ejecting the rinds from the cups as the cups approach the lower run, fluid jets mounted on the base and directed onto the upper and lower sides of the lower run of the series of cups; a baffle on the frame above the upwardly directed jet; a vapor jet discharging into the cups between the fluid jets and feeding means; and a removable pan disposed below said fluid jet.

14. In a juicing machine, spaced pairs of wheels having opposed notches in their peripheries, an endless series of cups running around said wheels and having oppositely extending lugs adjacent their rear ends adapted to successively engage the successive notches; pairs of chain links connecting adjacent pairs of lugs; inwardly extending projections on the pairs of links underlying the leading end of each cup and the trailing end of the preceding cup and adapted to maintain the cups in the plane of the links, each cup being of square shape and having a cross-shaped slot in its bottom; a circular lining within said cup tangent to the sides thereof; and inverted U-shaped springs, each having one leg anchored adjacent a corner of the cup, said springs extending radially over the lining and having their free ends extending downwardly towards the center of the lining.

FREDERICK L. McCULLOCH.
